UNITED STATES PATENT OFFICE.

EDWIN W. WEBB, OF CHICAGO, ILLINOIS, ASSIGNOR TO STANDARD CAR TRUCK COMPANY, OF CHICAGO, ILLINOIS, A CORPORATION OF NEW JERSEY.

SIDE BEARING.

Application filed November 2, 1922. Serial No. 598,525.

To all whom it may concern:

Be it known that I, EDWIN W. WEBB, a citizen of the United States, residing at Chicago, in the county of Cook and State 5 of Illinois, have invented certain new and useful Improvements in Side Bearings; and I do hereby declare the following to be a full, clear, and exact description of the invention, such as will enable others skilled 10 in the art to which it appertains to make and use the same.

This invention relates to a bearing for railway cars, and particularly to a side bearing adapted to be disposed between the truck 15 and body bolsters of such a car.

It is an object of this invention to simplify the structures of such a bearing, particularly of a three-part bearing, comprising a housing, bearing plate and roller 20 by constructing the same so that the bearing plate and roller can be inserted from the top of the housing.

It is a further object of the invention to provide such a bearing having a roller which 25 rolls on the bearing plate and moves longitudinally of the housing, which roller has an axially extending projection adapted to move in a recess in the housing, which recess has an upwardly extending portion 30 through which the said projection is adapted to pass when the roller is placed in the housing, the housing further having means to close said portion after the roller is inserted.

It is still another object of the invention to provide the housing with means adjacent its bottom which act both as tying or strengthening means for the housing and also as a supporting means for the bearing 35 plate which is insertable from the top of the housing.

These and other objects and advantages of the invention will be fully set forth in the following description made in connection 45 with the accompanying drawings in which like reference characters refer to the same parts throughout the different views, and in which,—

Fig. 1 is a plan view of the device, a portion thereof being shown in section;

Fig. 2 is a view in side elevation of the device, a portion thereof being shown in section;

Fig. 3 is a view partly in central vertical

section of the device and partly in end elevation thereof; and

Fig. 4 is a partial view in elevation of the inside of the housing.

Referring to the drawings, the device comprises a housing having side walls 1 with substantially smooth vertical inside portions and end walls 2 integral therewith. The end walls have substantially vertical inside surfaces for a short distance from the bottom of the housing and then curve outwardly 65 and upwardly and are provided with cut-out substantially semi-circular portions to permit the passing of fastening bolts, which latter pass through openings 3 formed in the flange 4 at the ends of the housing. The side and end walls, therefore, enclose a substantially rectangular opening adjacent the bottom of the housing. The corners of this opening at the bottom of the housing are filled in by substantially triangular portions 75 5, the inner edges of which are formed as substantially circular arcs and these portions 5 thus form webs which tie the side and end walls together and add to the strength and rigidity of the housing. The 80 housing, further, has outwardly extending flanges at its upper portion and on one side thereof a portion 6 extends downwardly along the side of the housing and a slot 7 extending inwardly from the inner side of the housing is formed in this portion, said slot having a horizontal bottom and a top wall extending upwardly from the central portion thereof so that the slot has slightly greater dimension at its end portions than at 85 its central portion. This slot 7 has at one end a portion 8 extending upwardly therefrom to the top of the housing.

A bearing plate 9 is disposed in the bottom of the housing, the lower portion of 90 which is shaped to be received between the triangular portions 5, said plate having corner portions 10 extending over and resting upon said triangular portions 5. The plate 9 is thus adapted to be inserted into 100 the housing from the top in the assembling of the device and this plate also has a flat top surface inclining downwardly toward the center thereof from each end. A bearing roller 11 is disposed in the housing and supported upon the plate 9. This roller has an axial projection 12 extending from one side thereof formed by a pin secured in said

roller and this projection is adapted to move in the slot 7 during the travel of the roller along the surface of plate 9. The roller 11 is also adapted to be inserted in the housing 5 from the top in the assembling of the device and, in such insertion the projection 12 will pass through the portion 8 of slot 7. After the roller has thus been inserted in the housing, the slot portion 8 is closed by 10 a bolt having a head 13 disposed in said slot portion. This bolt extends through an opening in the housing and is illustrated as having its head riveted over on the outside of the housing. One side of the roller 11 15 is formed with a flat face giving a large bearing and wearing surface against the inner side of the housing.

In operation, the bearing roller normally occupies the position shown in Fig. 2. 20 Upon relative movement of the surface engaging the top of the roller and the truck bolster, as when the car is going around a curve, the roller will be turned and travel in one direction or the other upon the bearing 25 plate 9. At this time, the projection 12 will move in the slot 7. As the roller travels up the incline toward the ends of plate 9 it will return to its central position by gravity. The roller is prevented from rising in the 30 housing by the projection 12 engaging the top of the slot 7 and this projection cannot, of course, move out of said slot through the opening 8 since the latter is closed by the 35 bolt head 13. As already stated, the device is assembled from the top, the corners 10 of the plate resting upon the corners 5 of the housing and the roller being inserted after the plate is inserted. The triangular 40 corners 5 thus not only form reinforcing means tying the walls of the housing together and adding to the strength and rigidity of the same, but also acts as a supporting means for the plate 9. It should be noted that the side walls of the housing are 45 continued as vertical flanges to the upper portion of the end walls so that a strong substantially rectangular housing is provided. The housing is provided with suitable cored openings to lessen the weight 50 thereof and it will be noted that the plate 9 is also provided with longitudinally extending cored slots.

From the above description it is seen that 55 applicant has provided an improved form of side bearing. The bearing is quite strong

and can be easily and conveniently assembled from the top. The bearing has been tested in actual practice and found very efficient for the purpose intended.

It will, of course, be understood that various changes may be made in the form, details, arrangement, and proportions of the parts without departing from the scope of applicant's invention, which, generally stated, consists in the matter shown and described and set forth in the appended claims.

What is claimed is:

1. A side bearing for railway cars having in combination, a housing, a bearing plate 70 therein, said housing having an opening adjacent its bottom with substantially vertical walls, substantially triangular portions at the corners of said walls below said opening forming reinforcing means for the housing and supporting means for said bearing plate, said plate being insertable from the top of said housing, and a roller supported on said bearing plate.

2. The structure set forth in claim 1, said 75 roller having an axially projecting portion, and said housing having a horizontal slot in which said projecting portion moves during the travel of the roller, said slot being constructed and arranged to permit the 80 insertion of said roller from the top of the housing.

3. The structure set forth in claim 1, said bearing plate having an upper portion substantially fitting in said opening adjacent 90 the bottom of the housing and having a lower portion disposed between said substantially triangular portions of the housing, the bottom of said latter portion being substantially flush with the bottom of the housing. 95

4. A side bearing for railway cars having in combination, a housing having side walls with substantially flat vertical inner surfaces, a bearing plate in the bottom of said housing insertable from the top thereof and supported on the bottom of said housing, and a bearing roller having an axial projection thereon, said roller also being insertable from the top of said housing, said housing having a longitudinally extending 100 slot in its side in which said projection travels, said roller being prevented from rising by the upper wall of said slot.

In testimony whereof I affix my signature.
EDWIN W. WEBB.
